Fig. 4. shows a detailed cross-sectional view of a mechanical assembly. The drawing includes various components labeled with numbers: 181, 311, 3/2, 103, 145, 96, 91, 141, 282, 111, 102, 104, 109, 97, 118, 121, 103, 106, 107, 143, 123, 308, 205, 187, 204, 201, 307, 199, 144, 83, 206, 135, 209, 210, 203, 197, 182, 185, 84, 192, 189, 191, 158, 153, 152, 149, 154, 145, 146, 187, 151, 157, 161, 159, 202, 198, 188, 164, 163, 125, 126, 106, and PUMP. The assembly features a central vertical structure with various shafts, bearings, and a pump unit on the right.

Fig. 11. shows a simplified schematic of a pump system. It includes a pump unit labeled "PUMP" connected to a vertical pipe assembly. The pipe assembly consists of a vertical pipe section with a valve, a horizontal pipe section with a valve, and a vertical pipe section with a valve. The entire assembly is labeled with numbers: 164, 163, 125, 126, 106, and PUMP.

Application March 22, 1946, Serial No. 656,323

2 Claims. (Cl. 214—1)

1

This invention relates generally to apparatus for feeding metal stock to a tool and particularly concerns a machine for feeding a metal tube or other cylindrical article into a swaging machine.

In the manufacture of metal tubes, it is the practice to point the tubes so they may be readily entered into a draw bench. The pointing operation has generally been accomplished by manually feeding the metal tube into a swaging machine and simultaneously turning the tube so it is uniformly pointed by the jaws of the swaging hammer. In some instances, a chuck has been utilized to hold the tube and feed it into the swaging machine and the chuck itself is rotated to turn the tube. When a chuck is used, it is necessary first to carefully align the chuck with the swaging hammer and then insert the tube into the chuck. After the swaging operation is completed, the tube must be withdrawn from the chuck. Insertion and withdrawal of the tube are awkward operations involving difficulties and delays which are undesirable. Furthermore, the chuck is subjected to considerable wear and tear from the shock of the blows struck by the swaging hammer on the end of the tube and transmitted by the tube to the chuck.

In order to make full use of continuous conveyor systems in the manufacture of metal tubes and other similarly shaped articles, it has become desirable to reduce the time delay of inserting the article in a chuck before feeding it to the swaging hammer. It is also desirable to eliminate manual operations by the use of automatic or semi-automatic devices.

It is a major object of this invention to provide improved feeding apparatus particularly adaptable for use in continuous type conveyor systems in which a tube may be easily supplied to the apparatus, quickly fed to a tool, and also easily discharged from the apparatus when the work of the tool is completed.

Another object of the invention is to provide apparatus usable in a continuous conveyor system for feeding a metal tube-like article to a tool and simultaneously turning the article as it is fed to the tool.

An important object of the invention is to provide improved and more durable feeding apparatus for a tube-like article by arranging a support on which the article may rest on a pair of rotating rolls for turning the article as it is fed to a tool, such as a swaging hammer.

A further object of the invention is to provide improved feeding apparatus for a tube-like arti-

2

cle in which the article rests on a support and is fed axially by a pusher element exerting thrust or endwise pressure on one end of the article.

A still further object of the invention is to reduce the transmission of impacts from a swaging hammer to the feeding apparatus by supporting the article being fed so it rests in a non-rigid position on a pair of rotating rolls in the feeding apparatus, thereby avoiding the direct transmission of the hammer impacts on the article to the feeding apparatus.

Other objects and advantages of the invention, particularly with regard to the arrangement and cooperation of the various parts, will become apparent from the following specification and accompanying drawings, wherein:

Fig. 1 is a diagrammatic plan drawing showing the track and related structural elements forming the foundation of a feeding apparatus embodying the invention;

Fig. 1a is like Fig. 1, but shows the withdrawn positions of the carriages;

Fig. 2 is a diagrammatic side elevation drawing showing in outline a complete machine for feeding metal tubes to a swaging hammer in accordance with the invention;

Fig. 2a is like Fig. 2, but shows the carriages as shown in Fig. 1a;

Fig. 3 is a side elevation view of the main supporting carriage shown diagrammatically in Fig. 2;

Fig. 4 is a top plan view of the main supporting carriage shown in Fig. 3;

Fig. 5 is an end view of the main supporting carriage as seen from the right-hand side of Fig. 3;

Fig. 6 is a vertical section of the main supporting carriage taken on the line 6—6 of Fig. 3;

Fig. 7 is a side elevation of the pusher carriage shown diagrammatically in Fig. 2, some parts being broken away for purposes of clearness;

Fig. 8 is a front elevation of the pusher carriage shown in Fig. 7, some parts being broken away for purposes of clearness;

Fig. 9 is a cross-section through the pit running between the tracks for the machine, showing the tracks and other associated structural elements which form the foundation of the feeding apparatus shown diagrammatically in Figs. 1 and 2;

Fig. 10 is a schematic diagram showing piping and cable connections between control devices and pneumatic cylinders that provide power for operations of the feeding apparatus shown in Figs. 1 and 2;

Fig. 11 is a schematic diagram of the hydraulic system for adjusting the vertical position of supporting rollers in the main supporting carriage shown in Figs. 3 to 6 inclusive;

Fig. 12 is a side elevation of a modified form of feeding apparatus embodying the invention;

Fig. 13 is a plan view of the feeding apparatus shown in Fig. 12;

Fig. 13a is a partial cross-sectional view taken on the line 13a—13a of Fig. 13;

Fig. 13b is a partial vertical sectional view taken on the line 13b—13b of Fig. 13a;

Fig. 14 is a vertical section taken on the line 14—14 of Fig. 12;

Fig. 15 is a vertical section taken on the line 15—15 of Fig. 12; and

Fig. 16 is a schematic diagram showing piping connections between control devices and pneumatic cylinders that provide power for operation of the feeding apparatus shown in Fig. 12.

According to the invention, two supporting rollers are mounted side by side in a carriage that moves along a track toward and away from a tool such as a swaging hammer. This pair of rollers receives a metal tube or other article from a receiving arm and holds it in substantial alignment with the tool with the heavier end of the article being disposed toward the steadyng rollers and the tool.

The supporting rollers are driven from a motor to turn the tube as it is fed into the swaging hammer. As the carriage moves to feed the tube to the swaging machine, a pusher member engages the trailing end of the tube. This pusher member moves with the carriage to supply the thrust required to force the tube into the hammer.

While it is recognized that some features of the invention are generally applicable to other types of feeding apparatus, the drawings illustrate preferred forms of the invention embodied in apparatus for feeding a metal tube to a swaging machine for pointing the end of the tube.

General structure

Figs. 1 and 2 are diagrammatic drawings of feeding apparatus having a foundation formed by a track consisting of laterally spaced rails 21 and 22 arranged on shoulders on opposite sides of a pit 23, which may be formed in the floor so the track is below floor level. The rails 21 and 22 provide a runway for a supporting carriage, designated generally at 24, which may carry a metal tube, indicated by dash lines at 25. The supporting carriage 24 moves along the track to feed the tube 25 axially into a swaging hammer 26. At the same time, the tube is turned, by apparatus to be described, as it is fed into the hammer to produce a uniformly pointed end on the tube. In order to supply the thrust necessary to force the tube axially into the swaging machine, a pusher carriage, designated generally at 27, also moves along the rails 21 and 22 and has a pusher member 28 movable on the pusher carriage to engage and supply endwise pressure to the trailing end of the tube 25.

The supporting carriage 24 and the pusher carriage 27 are coupled together, as, for example, by pins 31 and 32, which secure the respective carriages to a shifter rod 33 arranged between the track rails. As may be seen most clearly in Fig. 9, the shifter rod 33 is formed of a pair of laterally spaced channel members 34 and 35 having their upper flanges connected by a plate 36. For purposes of rigidity, a number of cross mem-

bers 39 may be connected between the webs of the channels. To provide a sliding support for the shifter rod 33, a plurality of pairs of rollers 41 and 42 on brackets 43 and 44 are arranged at spaced intervals on channels 45 and 46, which are carried in upright supports 51, 52, 53, 54 and 55 arranged at longitudinally spaced intervals in the pit 23. The rollers 41, 42 are mounted for rotation about transversely disposed horizontal axes and fit between the flanges of the channels 34 and 35, permitting free longitudinal movement of the shifter rod 33 along the track.

A plurality of holes 38, 38 are formed in the plate 36 of the shifter rod 33 to receive the pins 31 and 32 for coupling the two carriages. The supporting carriage 24 and the pusher carriage 27 may, therefore, be coupled in any desired spaced relation by the shifter rod to accommodate tubes of any desired length. Two positions of the pusher carriage are shown in Fig. 1. The position of the carriage 27 shown in full lines is for relatively short tubes. For longer tubes, the pusher carriage may be coupled at the end of the shifter rod 33 as indicated by the position of the pusher carriage at 27' indicated by dotted lines.

As will appear from the detailed description of the supporting carriage, the tube 25 is arranged in substantially balanced fashion on the supporting carriage 24. For this reason, the spacing between the pusher member 28, on the pusher carriage 27, and the main carriage 24 is somewhat critical, depending upon the length of the tube. Hence, the holes 38 are arranged at short intervals to permit coupling the two carriages in correctly spaced relation.

In order to move the supporting carriage 24 and the pusher carriage 27 along the rails 21 and 22 for feeding the tube 25 into the swaging hammer 26, a power cylinder 58 is preferably operated by pneumatic pressure transmitted through conduit 59 to a series of control valves within housing 61. These valves may be arranged to selectively supply pressure by way of conduits 63 and 64 to opposite ends of the power cylinder 58. The power cylinder 58 has a piston rod 65 connected by brackets 66 and 67 to the shifter rod 33. When the shifter rod 33 is moved by operation of the power cylinder 58, it moves the supporting carriage and the pusher carriage together along the track.

Supporting carriage

The supporting carriage 24 is shown in detail in Figs. 3 to 6 inclusive of the drawings and has a main base frame, designated generally at 71, composed of two pairs of longitudinally extending channel members 72, 73 and 74, 75 secured in transversely spaced relation by cross members 71, 71. To support this frame 71 for movement along the rails 21 and 22, flanged wheels 78 and 79 are journaled between the channels 72 and 73 on one side of the carriage and wheels 81 and 82 are journaled between the channels 74 and 75 on the opposite side. An upper portion of the main frame is formed of longitudinally extending angles 83 and 84 supported on the base frame by upright members 85, 85 and connected by a plurality of cross members 86, 86 to rigidly hold the longitudinal angles in transversely spaced relation.

A movable frame, designated generally at 91, has an upper platform formed of a plate 92 and a lower platform 93 connected by vertical members 94 and 95. This movable frame 91 is in

the nature of a sub-assembly or sub-frame which is slidable vertically with respect to the main frame. The movable frame 91 is guided by four vertically disposed angle members 96, 97, 98 and 99 mounted on the main frame 71 and is squared horizontally by a torque shaft 141, which is connected, as by links 142 and 143, to the upper platform 92. The torque shaft 141 is arranged to slide in grooves formed by the horizontal flanges of angle members 83 and 84 and horizontal flanges of angle members 144 and 145, which are mounted on the angles 83 and 84 and spaced below the horizontal flanges thereof.

The upper platform 92 of the movable frame 91 carries horizontally disposed supporting rollers 101 and 102, which are preferably rubber-tired. These supporting rollers are mounted side by side on parallel shafts 103 and 104 carried in suitable bearings 106, 107 and 108, 109 for rotation about laterally spaced longitudinal axes. A motor 111, which may be electrically controlled to rotate a tube at various speeds, is carried by the movable frame 91 on the lower platform 93 and has its drive shaft 112 keyed to one plate 113 of a resilient coupling 114.

The resilient coupling 114 includes a spring 115 connected between the plate 113 and a similar adjacent plate 116, which is freely rotatable on the drive shaft 112. These plates are arranged in scissors fashion so power from the motor 111 is transmitted by plate 113 through the spring 115 to turn the plate 116. A sprocket 117 is secured to the plate 116 so it is driven by the resilient coupling 114 from the motor 111. The sprocket 117 is arranged to drive chain 118, which drives sprockets 119 and 121, on the shafts 103 and 104, respectively. In this manner, shafts 103 and 104 rotate the rubber-tired rollers 101 and 102 to turn the tube 25 as it is fed to the swaging machine. In order to adjust the slack in the chain 118, a take-up sprocket 119' is pivoted by link 120 to the vertical member 94 of the movable frame and is adjustable vertically by a bolt 122 and a nut 123 secured to the upper platform 92.

The vertical position of the movable frame 91 with respect to the main frame 71 may be varied by manipulation of a hand pump 125 (Fig. 11). This pump supplies pressure fluid through a valve 126 to a pair of hydraulic cylinders 127 and 128 having their lower ends pivotally connected, as at 129 and 131, to brackets 132 and 133 on the channel members 73 and 74 of the main frame. Piston rods 134 and 135 of the hydraulic cylinders 127 and 128 are pivotally coupled, as at 136 and 137, to the upper platform 92 of the movable frame 91. When pressure fluid is supplied from the pump 125 to the cylinders 127 and 128, piston rods 134 and 135 raise the movable frame 91 with respect to the main frame 71.

The purpose of the vertical adjustment of the movable frame 91 is to facilitate alignment of the rollers 101 and 102 with the swaging hammer 26 so a tube supported on the rollers will enter between the jaws of the hammer. As the tube is fed into the swaging hammer, the rotation of rollers 101 and 102, driven by the motor 111, acts to turn the tube with respect to the swaging hammer. When the jaws of the swaging hammer strike and grip the tube, rotation of the tube is, of course, momentarily arrested. In order to avoid damaging the rubber-tired rollers 101 and 102 or stalling the motor 111, the resilient coupling 114 permits the tube and rollers to stop rotating without interrupting operation of the

motor during the brief intervals that the swaging hammer grips the tube.

The tube 25 may be placed on the rubber-tired rollers 101 and 102 so it is exactly balanced. However, it is preferable to have the tube slightly unbalanced, with its heavier end toward the swaging machine 26 so it may rest on a pair of steady rollers 146 and 147. These steady rollers are mounted on shafts 148 and 149 for rotation about laterally spaced longitudinal axes. The shafts 148 and 149 are carried by frames 151 and 152, which may be relatively adjusted transversely of the supporting carriage by turning hand crank 153 connected to a lead screw 154 threaded through the frames 151 and 152. In this manner, the lateral spacing of the shafts 148 and 149 may be adjusted according to the diameter of the tubes that are being fed to the swaging machine.

The frames 151 and 152 for the steady rollers are carried by a bracket 156 pivoted between arms 157 and 158, which are fixed on shaft 159 journaled in the main frame of the supporting carriage. The shaft 159 is arranged to be turned by an arm 161 keyed on the shaft and pivotally connected at 162 to piston rod 163 of a hydraulic cylinder 164. A link 165, pivotally connected between the bracket 156 and the arm 161, completes a parallel linkage that acts to maintain the bracket 156, as well as the steady rollers 146 and 147, in an upright position.

The vertical position of the steady rollers 146 and 147 may be adjusted by operation of the manually controlled pump 125, which is connected through valve 166 to the hydraulic cylinder 164 having its cylinder pivotally connected at 167 to one arm 168 of a bell crank 169. The bell crank 169 is pivotally mounted at 171 in the main frame and has its other arm 172 connected to one end of a tension spring 173, the other end of which is connected by eye-bolt 174 to the upper portion of the main frame. By placing the spring 173 under an initial tension, a resilient mounting is provided for the steady rollers.

When a tube to be pointed is resting on the rubber-tired rollers 101 and 102, the steady rollers 146 and 147 may be raised by operation of the hydraulic cylinder 164 to support the heavier end portion of the tube as it is fed into the swaging machine. Usually the steady rollers will be positioned to hold the end of the tube slightly above the lower jaw of the hammer so it will not strike the hammer when the carriages are moved. With the tube substantially balanced on the rubber-tired rollers 101 and 102, the shock of the swaging hammer striking the tube will not be transmitted through these supporting rollers to the supporting carriage. The steady rollers 146 support one end of the tube just above the lower jaw of the swaging hammer so they receive a substantial jar each time the jaws close to strike the tube. Since the steady rollers are spring reacted, the effects of the hammer blows are substantially absorbed. In this way, spring 173 provides a resilient cushion that absorbs impacts affecting the steady rollers 146 and 147 and prevents these impacts from being transmitted to the remainder of the supporting carriage.

As has been previously stated, the present invention is particularly intended for use in connection with continuous type conveyer systems. Tubes may be rolled one at a time, either automatically or manually, onto receiving arms 181 and 182, which are affixed, as by welding, to a

shaft 183 extending longitudinally along one side of the main frame. The shaft 183 may be mounted for rotation in bearings 184 and 185 carried on the upper portion of the main frame. The receiving arms are arranged at opposite ends of the supporting carriage and are provided with depressed portions 187. The shaft 183 is normally positioned so the depressed portions of the receiving arms 181 and 182 will hold the tube just above the rubber-tired rollers 101 and 102 and the steadyng rollers 146 and 147 as shown in Fig. 5.

After a tube is placed on the receiving arms 181 and 182, the shaft 183 is turned to lower the arms and rest the tube on the supporting rollers. The receiving arms then descend to a lower position as shown in Fig. 6. To move the receiving arms in this manner, a power cylinder 188 is carried on the main frame 71 of the supporting carriage by brackets 190, 190. The cylinder 188 has its piston 189 pivotally connected, as at 191, to a pair of arms 192, 192 fixed on the shaft 183 for turning the shaft to raise or lower the receiving arms. The power cylinder 188 is preferably pneumatically operated by compressed air supplied through armored cable 193 to a solenoid-operated control valve 194 carried by the main frame 71 of the supporting carriage. As shown in Fig. 10, this valve controls the distribution of the compressed air to the power cylinder 188 and thereby controls the direction of movement of the piston rod 189.

In order to discharge the tube 25 from the supporting carriage 24 after the swaging operation is completed, discharging or kick-out arms 197 and 198 are rigidly mounted, as by welding on the end portions of a shaft 199. The shaft 199 extends along the opposite side of the supporting carriage from the shaft 183 and is rotatably mounted in bearings 201 and 202 carried on the upper portion of the main frame. The shaft 199 is normally positioned to hold the discharging arms below the tube 25 as shown in Figs. 5 and 6. Upward movement of the kick-out arms to discharge the tube is effected by a power cylinder 203 carried on the main frame 71 by brackets 207, 207 and having its piston rod 204 pivotally connected at 205 to a pair of arms 206, 206, also fixedly mounted on the shaft 199. The power cylinder 203 is preferably pneumatically operated by compressed air supplied through the armored cable 193 and distributed by a solenoid-controlled valve 208 to control the direction of movement of the piston rod 204. As the piston rod 204 moves, it acts through arms 206, 206 to rotate the shaft 199 and thereby raise or lower the kick-out arms 197 and 198, depending upon the direction in which the piston rod is moved.

The supporting carriage may be coupled to the shifter rod 33 by placing the pin 31 through a hole 210 formed in plate 209 extending rearwardly from the main base frame 71.

Pusher carriage

The pusher carriage 27 is shown in detail in Figs. 7 and 8. This pusher carriage, like the supporting carriage, has a main base frame 211 composed of channel members 212, 213 and 214, 215 arranged in pairs on opposite sides of the carriage and connected by end plates 216 and 217 to form a rigid framework. Four wheels 218, 218 are arranged at the four corners of the carriage to support it for rolling movement along the rails 21, 22. Two channel members 221 and 222 are arranged in vertically spaced relation 75

so their adjacent flanges form a guideway extending longitudinally along one side of the pusher carriage. Two other channel members 223 and 224 are similarly arranged on the other side to form another guideway. These guideways provide laterally spaced parallel tracks permitting longitudinal movement of a pair of transversely disposed rollers 225 and 226 extending between angle members 227 and 228. These angle members form a movable frame supported by the rollers 225 and 226 for longitudinal movement with respect to the base frame 211 of the pusher carriage. This movable frame is retained in a centrally located position by a plurality of roller flanges 229, 229, which may be welded on the faces of the rollers 225 and 226 in position to engage the web portions of channel members 221, 222 and 223, 224.

A rod 231, which is journaled in the angle members 227 and 228, carries a pair of upright angle members 232 and 233 supporting the pusher member 28, which is formed by a cylindrical target element 235 mounted on a plate 236 fastened to the upright members 232 and 233. The upright members 232 and 233 are secured to horizontal angle members 237 and 238, as well as a pair of braces 241 and 242, to form a rigid framework pivotally supporting the pusher member 28 on the movable frame of the pusher carriage. The target element is normally retained in an upright position by a compression spring 243, which is arranged between the angle member 237 and the angle member 227 of the movable frame, as well as a similar spring 243 that is arranged between the angle members 228 and 238, the springs being normally precompressed by a bolt, such as that shown at 244, which is threaded in a nut 245.

To effect reciprocation of the movable frame carrying the pusher member 28, a power cylinder 247 is carried in a horizontal position on the main frame 211 by brackets 248 and 249. This power cylinder 247 has a piston rod 251 coupled to a block 252 extending between and fastened to plates 253 and 254, which depend from the movable frame carrying the pusher member 28. These plates 253 and 254 are arranged to transmit the motion of the piston rod 251 directly to rod 231 for moving the movable frame longitudinally on the pusher carriage. In this manner the target 235 may be moved over the end of a tube and the pusher member moved into engagement with the end of the tube.

When the tube is thus contacted by the plate 236 of the pusher member 28, the framework pivots on the rod 231 against the action of the compression springs. When this occurs, a switch 255, which is mounted on angle member 238 and has its actuating lever 255 connected to angle member 228, is operated to arrest further longitudinal movement of the movable frame so the pusher member 28 is held by compression spring 243 against the end of the tube.

Power for the cylinder 247 is supplied through cable 261 and is preferably in the form of compressed air from the same source as that which supplies the other power cylinders in the apparatus. Since this cable 261 must be long enough to reach between the carriages 24 and 27 when they are spaced a maximum distance on the shifter rod 33, an adjustable cable support 262 is pivoted, as at 263, in a bracket 264 carried by the main frame 211 of the pusher carriage. The cable support 262 has a pulley 266 rotatable in a bracket 267 at its upper end. The position

of this pulley 266 may be raised and lowered by a hydraulic cylinder 268, which is connected between the main frame 211 and the cable support 262. The operation of the hydraulic cylinder is controlled by a manually operable pump 269, which may be actuated by lever 271 to supply hydraulic fluid through conduit 272 to the cylinder 268. When the distance between the carriages is shorter, the pulley 266 on the cable support 262 is raised; and when this distance is greater, an exhaust valve may be opened by operation of handle 274 to lower the pulley 266.

The pusher carriage 27 may be connected at any point along the shifter rod 33 by inserting the pin 32 through a hole 276 formed in one flange 277 of a bracket member secured to the main frame 211.

Operation

In operation of the apparatus to feed a tube such as that shown at 25 to a swaging hammer 26, the supporting carriage 24 and the pusher carriage 27 are coupled to the shifter rod 33 at points selected to accommodate the length of the tube to be pointed. After the carriages are coupled, the position of the pulley 266 on the pusher carriage is adjusted by operation of hydraulic cylinder 268 to raise the cable 261 so it will not drag along the floor of the pit 23 as the carriages are moved along the track. The rubber-tired rollers 101 and 102 are then adjusted vertically by actuating pump 125 to control the supply of hydraulic pressure to cylinders 127 and 128 for raising or lowering the movable frame 91 of the supporting carriage until a tube supported on the rubber-tired rollers is substantially aligned with the swaging hammer 26. Steadyng rollers 146 and 147 are adjusted transversely by handle 153 to accommodate the particular tube and are also positioned vertically by actuating hydraulic cylinder 164 so they will hold the tube 25 just above the lower jaw of the swaging hammer 26.

After these adjustments have been made, the motor 11 is started to drive the rollers 101 and 102. A single tube 25 is then rolled onto the receiving arms 181 and 182, which, as has been previously explained, are normally positioned so their depressed portions 187 will receive and hold the tube just above the periphery of the rubber-tired rollers 101 and 102. As the tube rolls along the receiving arms toward these depressed portions, it depresses a lever 281 to actuate a switch 282 (Fig. 4), which energizes a solenoid 283 (Fig. 10) to control the valve 194 to supply compressed air through conduit 284 so the piston in power cylinder 188 moves the piston rod outwardly. This turns the shaft 183 in a direction to lower the receiving arms and the tube 25, which is thereby placed in substantially balanced position, onto the rubber-tired rollers 101 and 102. The tube is so arranged that its heavier end is toward the swaging hammer 26 so it will also rest on the steadyng rollers 146 and 147. Since the motor 11 is operating, the rollers 101 and 102 immediately begin turning the tube.

The operator then actuates an "in" push button which energizes solenoid 285 (Fig. 10) to operate distributing valve 286 so it supplies compressed air from the conduit 59 to the main power cylinder 58 by way of the conduit 63, thereby moving the piston rod 65 inwardly so both the supporting carriage 24 and the pusher carriage 27 move from the positions shown in Figs. 1a and 2a, to feed the tube 25 toward the swaging machine 26. Operator of this "in" push button also energizes solenoid 287 (Fig. 10), which

controls valve 288 so air exhausted from the power cylinder 58 through the distributing valve 286 is exhausted through passage 289 to an exhaust conduit 290. The operation of the same "in" push button further energizes solenoid 291 to operate distributing valve 292 so compressed air supplied from cables 193 and 261 passes through conduit 293 to the power cylinder 247 and moves the piston rod 251 outwardly to move the pusher member 28 toward the tube 25. It will be apparent, therefore, that actuation of the "in" push button by the operator causes the two carriages to move rapidly toward the swaging hammer and at the same time causes the pusher member 28 to move in the same direction to engage the trailing end of the tube 25.

Thus, the pusher member moves from its dotted position 28' to the full line position (Fig. 2). When the pusher member 28 contacts the end 20 of the tube 25, the framework supporting the pusher member pivots about the rod 231 against the compression of spring 243 to actuate the switch 255 as previously explained. Actuation of the switch 255 de-energizes the solenoid 291 (Fig. 10) so the distributing valve 292 closes the conduit 293 and locks the piston in power cylinder 247 to retain the pusher member in engagement with the end of the tube.

As the carriages move the tube toward the swaging hammer; a cam 294 (Fig. 1), carried by an arm 300 on the shifter rod 33, engages a lever 295 to actuate switch 296, which is supported beside the path of movement of the shifter rod 33. Actuation of the switch 296 de-energizes the solenoid 287 which shifts valve 288, so air exhausted from the main cylinder 58, through distributing valve 286, is exhausted through a restricted passage 297 (Fig. 10) to the exhaust conduit 290, thereby retarding the speed of the piston rod 65 so the carriages are moved to feed the tube 25 more slowly, at a "feeding speed," into the swaging hammer. This switch 296 is preferably so positioned that it is actuated just before the tube enters the swaging hammer 26.

45 As the tube is being slowly fed by the carriages and at the same time turned so it will be uniformly pointed by the swaging hammer, the thrust or endwise pressure necessary to force the tube between the jaws of the hammer is applied by the pusher member 28. The operator may at 50 any time stop the feeding of the tube 25 by actuating a "stop" push button to energize solenoid 298 (Fig. 10), which operates valve 299 to cut off the exhaust of air from conduit 290 thereby locking the piston in power cylinder 58.

If the feeding is not stopped, the carriages will continue slowly moving toward the swaging hammer until the operator actuates an "out" push button to reverse movement of the carriages.

60 This "out" push button de-energizes the solenoid 285 to reverse the connections of the distributing valve 286 so air is supplied to the power cylinder 58 to move the piston rod 65 outwardly. The "out" push button also energizes solenoid 287

65 so air exhausted from the cylinder passes through unrestricted passage 289 and permits rapid reverse movement of the carriages. Solenoid 301 is also energized by the "out" push button to operate distributing valve 292 so compressed air from cable 261 is supplied to the power cylinder 247 to move the piston rod 251 inwardly and thereby withdraw the pusher member 28 from the end of the tube 25.

When the tube has been withdrawn from the hammer, a cam 302 (Fig. 1) on the shifter rod

33 engages actuating lever 303 on switch 304, which is thereby operated to de-energize the solenoid 287 (Fig. 10) to slow down the exhaust of air from the main cylinder 58 and thereby reduce the speed of the reverse movement of the carriages. Actuation of the switch 304 also energizes solenoid 305 to position valve 208 so compressed air is supplied through conduit 306 to the rod end of power cylinder 203 for moving the piston rod 204 inwardly so the shaft 199 is rotated to raise the discharging arms 197 and 198, which lift the tube 25 from the rollers 101 and 102 and discharge the tube from the feeding apparatus.

As the tube rolls off the discharging arms 197 and 198, it actuates lever 307 (Fig. 4) to operate a switch 308. Operation of the switch 308 de-energizes the solenoid 283 so the valve 194 supplies compressed air through conduit 309 to the rod end of power cylinder 186, moving the piston rod 189 inwardly to raise the receiving arms 181 and 182 to their normal position above the supporting rollers 101 and 102. When the receiving arms reach their normal position, lever 311 is moved to actuate limit switch 312, which de-energizes the solenoid 305 to position valve 208 so compressed air is supplied through conduit 313 to power cylinder 203 for moving the piston rod outwardly and thereby lowering the discharging arms to their normal position below the periphery of the supporting rollers 101 and 102.

In the event the operator does not actuate the push button for reversing the apparatus to withdraw the tube from the hammer, when the piston rod 65 is moved to its innermost position in the power cylinder 58, the cam 302 on the shifter rod engages lever 315 to actuate limit switch 316, which de-energizes the solenoids 285 and 287 and also energizes the solenoid 301 so the main power cylinder 58 rapidly moves the carriages to withdraw the tube from the swaging hammer and the pusher member 28 is withdrawn from the end of the tube.

Modified construction

In some applications of feeding apparatus of the type herein described, it is necessary to accommodate heated tubes. As the temperature of the tubes may be raised to the point of "red heat" before they are fed to the swaging apparatus, such a high temperature might damage the rubber supporting rollers used in the feeding apparatus illustrated in Fig. 1. To accommodate heated tubes, the modified construction illustrated in Figs. 12 to 15 differs from the previously described feeding apparatus in that metal supporting rollers are used to support and turn the tube as it is fed into the swaging hammer. Friction necessary for turning the tube during the swaging operation is provided by a pinch roll which applies pressure to the upper portion of the tube to increase its frictional engagement with the supporting rollers.

Other distinguishing features of this modified construction are: the provision of a power driven jack roll for moving the tube into engagement with the pusher element, thereby permitting the pusher element to be mounted in a stationary position on the feeding carriage; the arrangement of the feeding carriage for movement on an adjustably positionable main carriage to accommodate different lengths of tubes without requiring separate carriages for the supporting rollers and the pusher element; and the arrangement of one receiving arm and one discharging arm in fixed

positions with respect to the swaging hammer and a second receiving arm as well as a second discharging arm mounted on the feeding carriage.

The feeding apparatus shown in Figs. 12 to 15 is arranged on a solid base 401, which may be the concrete floor of the building in which a swaging hammer 402 is housed. A pair of rails 403 and 404, fixed to the base 401, provide a runway on which a main carriage, designated generally as 10 405, is supported. This main carriage is constructed with a rectangularly shaped frame formed of four longitudinal channels 406, 407, 408 and 409 arranged in pairs on opposite sides of the carriage and connected by transverse channels 15 411 and 412. Each pair of longitudinal channels carries a plurality of wheels 413, 413 spaced along the length of the frame to provide a multi-wheeled support permitting movement of the main carriage along the tracks 403 and 404.

20 A feeding carriage, designated generally at 414, is constructed similarly to the main carriage 405 with a rectangular base frame formed of four longitudinal channels 416, 417, 418 and 419 arranged in pairs on opposite sides of the frame and connected by transverse channels 421 and 422. The pairs of channels on the feeding carriage carry wheels 423, 423 for supporting the feeding carriage on rails 424 and 425 extending longitudinally of the main carriage 405.

30 With this arrangement, the main carriage may be positioned longitudinally of the base rails 403 and 404 at any desired distance from the swaging hammer 402 to accommodate various lengths of tubes and may be fixed in such position by a pin 35 426 carried in a bracket 427 connected to the transverse channel 412 of the main carriage. To feed the tube into the swaging hammer, the feeding carriage is moved longitudinally of the main carriage as by an air cylinder 428 supported by 40 bracket 429 on a plate 431 carried between channels 432 and 433 in the rectangular framework of the main carriage. The air cylinder 428 has a piston rod 434 pivotally connected as at 435 to an arm 436 depending from the framework of the 45 feeding carriage.

A pair of supporting rollers 441 and 442 are journaled in brackets 443 and 444 carried on a vertically adjustable platform formed of angle irons 445 and 446. The angle irons are provided 50 at their ends with plates 447, 447 which slide on vertical guides in the form of channels 448, 448 extending upwardly on opposite sides of the feeding carriage. A horizontally disposed plate 449 connected between the angles 445 and 446 provides a support on the vertically adjustable platform for an electric motor 451 which drives, through reduction gears in gear box 452, a sprocket 453 and a chain 454 to turn sprockets 455 and 456 keyed to the shafts of the rollers 441 and 60 442 to rotate the supporting rollers. An adjustable take-up sprocket 457 may be arranged below the supporting rollers to take up slack in chain 454. As will be apparent from the drawings, the supporting rollers 441 and 442, the motor 451, as 65 well as the driving chain and sprockets, are movable as a unit with the vertically adjustable platform.

To move and hold the platform in any position to accommodate tubes of varying diameters, 70 a pair of lead screws 458 and 459 are journaled in bearings 461, 461, mounted on the feeder carriage and threaded in nuts 462 and 463 fixed to the platform. The lead screws 458 and 459 may be connected in driving relation by a chain 464 75 on sprockets 465 and 466, which are mounted on

the respective lead screws. The lead screw 458 is provided with a squared end 457 adapted to receive a wrench for simultaneously turning both screws to raise or lower the platform.

A pusher element 468 is carried by upright channels 469, 469 pivotally mounted at 471 on the framework of the feeder carriage and urged forwardly toward a tube on the supporting rollers by a compression spring 472 arranged between the framework of the feeder carriage and a channel member 474 mounted between channel members 475, 475 extending horizontally from the upright channels 469.

When the tube 450 has been placed on the supporting rollers 441 and 442 and is in engagement with the pusher element 468, a pinch roll 477 is forced downwardly on top of the tube to provide increased driving friction between the tube and the supporting rollers. The pinch roll 477 is journaled in arms 478, 478 which are pivotally supported in brackets 479, 479 mounted on one of the channel members 448. At one end, the arms 478 are pivotally connected at 481 to piston rod 482 of an air cylinder 483, which is pivotally mounted at 484 in brackets 485, 485 carried by channels 486, 486 extending transversely between the upright channels 448.

A pair of receiving arms 491 and 492 are arranged to receive the tube 450 as it is rolled from skids 493. The receiving arm 491 is carried by a shaft 494 (Fig. 15) which is journaled in bearing blocks 495, 495 mounted on angles 496, 496 extending transversely between upright angles 497, 497 and carried by the framework of the feeder carriage. The receiving arm 492 is supported in a similar manner on a shaft 498 which is journaled in bearing blocks 499, 499, carried by transversely disposed angles 501, 501 extending between upright angles 502, 502 of a framework attached to the base by stationary brackets 503, 503 adjacent the swaging hammer 402. The receiving arm 492, which is adjacent the swaging hammer, supports one end portion of the tube as it is rolled from the skids 493 and the receiving arm 491, which is adjustable with the main and feeding carriage according to the length of the tube, is positioned to receive the other end portion of the tube. Both of the receiving arms are provided with depressed portions such as the portion 505 shown in Fig. 15 for the arm 491 so the tube 450 will roll along the receiving arms into the depressed portions which center it with respect to the swaging hammer. For the purpose of raising or lowering the receiving arms 491 and 492, the shafts 494 and 498 are provided with cranks 506 and 507 respectively. The crank 506 is pivotally connected to a piston rod 508 of a pneumatic power cylinder 509 which is carried on stub shafts journaled in bearing blocks carried by members extending transversely of the framework for the feeder carriage. Similarly the crank 507 is connected to piston rod 511 of a pneumatic power cylinder 512, which is carried by stub shafts 513, 513 journaled in bearing blocks 514, 514 mounted on the stationary framework adjacent the swaging hammer 402.

When the tube 450 rolls onto the receiving arms 491 and 492, it is lowered onto jack rolls 515 and 516. These jack rolls have a V-shaped surface contour and are mounted for rotation about transverse axes to permit longitudinal movement of the tube with respect to the feeder carriage and the stationary framework. The jack roll 515 is mounted on a shaft 517 jour-

naled in vertically movable jack members 519, 519 which are carried by a plurality of links 521, 521 mounted on transversely disposed shafts 522 and 529 journaled in a pair of the upright members 497. The jack members 519, together with the links 521 and the upright members 497, form a parallel linkage. When the shaft 522 is turned, as by movement of cranks 524, 524, the jack members 519 move the jack roll 515 vertically. The cranks 524 are connected to piston rod 525 of an air cylinder 526, which may be supplied with pneumatic pressure to raise or lower the jack roll 515. Depending upon the diameter of the tube 450, the limit of the jack roll's upward movement is determined by a bolt 527 threaded in a bracket 528 on one of the angles 496 to engage the crank 524 when the jack roll has been moved to a desired position. A sprocket 510 on the shaft 517 may be driven by a chain 518 from a sprocket on countershaft 520 journaled in jack members 519. The countershaft 520 is driven by a suitable chain and a sprocket from a stationary shaft 523 journaled in upright members 497. The stationary shaft 523 is in turn driven as by a chain 530 from an electric motor 541.

The jack roll 516 is mounted on a shaft 531 journaled in jack members 532, 532 carried by links 533, 533 on shafts 534 and 535, which are journaled in a pair of transversely spaced upright members 502, 502 of the stationary framework. The shaft 534 carries cranks 536, 536, which are connected to piston rod 537 of an air cylinder 538. Pneumatic pressure supplied to the air cylinder operates the crank 536 to turn the shaft 534 so the parallel linkage of jack member 532, links 533 and upright member 502 causes vertical movement of the jack roll 516. As in the case of the jack roll 515, upward movement of the jack roll 516 is limited by a screw 539 carried in a bracket 540 mounted on the angle 501 of the stationary framework.

With the jack rolls 515 and 516 in their uppermost position, as determined by the screws 527 and 539, the receiving arms 491 and 492 lower the tube 450 onto the jack rolls. The jack roll 515 is then power driven from electric motor 541 to move the tube 450 rearwardly with respect to the feeder carriage and into engagement with the pusher element 468. As the air cylinder 428 moves the feeder carriage so the tube 450 enters the swaging hammer 402, the jack rolls 515 and 516 are simultaneously lowered by operation of their respective air cylinders 526 and 538 to properly place the tube in the hammer and support the opposite end of the tube on the supporting rollers 441 and 442. These supporting rollers, which are continuously driven by the motor 451, serve to support and rotate the tube 450 as the pusher element 468 supplies the thrust for feeding the tube into the hammer. Driving friction between the tube 450 and the supporting rollers 441 and 442 is maintained by the downward force exerted by the pinch roll 477.

After the tube is pointed, it is removed from the swaging hammer and raised by the jack rolls. The jack roll 515 is at this time driven to move the tube forwardly away from the pusher element 468 after which a pair of "kick-out" or discharging arms 542 and 543 raise the tube from the jack rolls and discharge it onto skids 544. The discharging arm 542 is mounted on a shaft 545 journaled in bearing blocks 546, 546 arranged on the transverse angle members 496, 496. The arm 542 is raised or lowered by an air cylinder

547 mounted on stub shafts 548, 548 journaled in brackets 549, 549 depending from the transverse angles 496, 496. Piston rod 551 of the cylinder 547 is connected by a crank 552 on the shaft 545 so pneumatic pressure supplied to the cylinder 547 turns the crank 552 to raise or lower the discharging arm 542.

Discharging arm 543 is mounted on shaft 553 carried in bearing blocks 554, 554 on transverse angle members 501, 501 of the stationary framework. An air cylinder 555 supported in the stationary framework has its piston rod 556 connected to cranks 557, 557, on the shaft 553 so pressure supplied to the cylinder 555 turns the cranks 557 to raise or lower the discharging arm 543.

In operation, the main carriage is positioned longitudinally of the tracks 403 and 404 according to the length of tube to be handled. The screws 527 and 539 are adjusted to limit the upward movement of the jack rolls 515 and 516 to suit the diameter of the tube, and lead screws 458 and 459 are adjusted so the supporting rollers 441 and 442 are positioned vertically to support the tube 450 in alignment with the swaging hammer 402. At the beginning of a cycle of operations, the feeder carriage is at the rear of the main carriage, as shown in Fig. 12; the pinch roll 477 is in its uppermost position, as shown in Fig. 14; the jack rolls 515 and 516 are in their lower position, as shown in Fig. 12; the "kick-out" arms 542 and 543 are in their lower position; and the receiving arms are positioned to support the tube 450 in their respective depressed portions so the entering tube is held above the jack rolls.

To feed a tube from the skids 493, the operator actuates an escapement device, designated 561, so a single tube rolls onto the receiving arms 491 and 492. As the tube rolls along the receiving arms toward the center of the machine, it actuates a pivoted arm 562 of a switch 563, supported on a bracket 564 on the receiving arm 491 and actuates a similar switch 565 on the receiving arm 492. These switches are connected in series and when simultaneously actuated by a tube rolling properly along the receiving arms energizes a solenoid 566 (Fig. 16) for operating a valve 567 to supply pneumatic pressure from conduit 568 to conduit 569, which is connected to the piston rod (outer) ends of each of the air cylinders 509 and 512. At this time, the other (inner) ends of cylinders 509 and 512, which are connected to conduit 571, are placed in communication with exhaust conduit 572. In this manner, the pistons in the cylinders 509 and 512 are moved inwardly to lower the receiving arms 491 and 492 and the tube carried by them. Adjustable ball check valves 573 and 574 are placed in the conduits 569 and 571 respectively to permit the free flow of pressure fluid toward the cylinders 509 and 512, but restrict the flow of pressure exhausted from these cylinders, thereby serving to control the speed of the pistons in the cylinders depending upon the adjustment of the valves.

The switches 563 and 565 also energize the solenoid 575 which positions valve 576 to supply pressure fluid from the conduit 568 to a conduit 577. The conduit 577 is connected to the piston (inner) ends of cylinders 526 and 538 so the pressure fluid raises the pistons in these cylinders to simultaneously raise the jack rolls 515 and 516. Fluid exhausted from the piston rod (outer) end of the cylinders passes through conduit 578 and the valve 576 to exhaust conduit 572. Ball check throttle valves 579 and 581 in the lines 577 and 578 control fluid exhausted from the cylinders

526 and 538 to govern the speed of the pistons in the cylinders. The cylinders 526 and 538 thus raise the jack rolls 515 and 516 as the receiving arms 491 and 492 are lowered so the tube 450 rests on the jack rolls.

The switches 563 and 565 also energize the motor 541 to drive the jack roll 515, thereby moving the tube 450 toward the pusher element 468 on the feeder carriage. In addition, the switches 563 and 565 energize the solenoid 582, which operates valve 583 to connect pressure fluid from conduit 568 through conduit 584 to the rod end of the cylinder 428. These switches also energize solenoids 585 and 598 to open normally closed valves 586 and 599 so conduit 587 from the other end of the cylinder 428 is placed in direct communication with the exhaust conduit 572. The pressure fluid in the cylinder 428 moves the piston therein to move the feeder carriage at maximum speed toward the swaging hammer. When the tube is about to enter the hammer, a cam 588 supported below the framework of the feeder carriage engages an arm 589 of a switch 591 supported on the main carriage. Actuation of the switch 591 de-energizes the solenoid 585 to close the slow-down valve 586 so fluid exhausted from the cylinder 428 through conduit 587 must pass through adjustable throttle valve 592 which is so set that the feeder carriage moves the tube into the hammer at correct hammering speed.

When the tube enters the hammer 402 the operator actuates an electrical push button which de-energizes the solenoid 575 reversing the position of valve 576 so the cylinders 526 and 538 are connected to lower the jack rolls 515 and 516. This push button also stops the motor 541 for driving the jack roll 515 and energizes a solenoid 593 which operates valve 594 to connect conduit 595 from the upper (piston) end of air cylinder 483 to the pressure conduit 568 for moving the pinch roll 477 downwardly into engagement with the tube 450. A pressure regulating valve 596 controls the pressure applied by the cylinder 483. With the solenoid 593 energized, the valve 594 connects conduit 597 from the lower end of the cylinder 483 to the exhaust conduit 572. As the jack rolls are lowered they lower the tube 450 onto the supporting rollers 441 and 442 which are continuously driven by the motor 451, so the tube 450 is turned as it is fed into the swaging hammer, the axial thrust for the tube being supplied by the pusher element 468 with a resilient force determined by the compression spring 472.

When the hammering operation is completed, the operator actuates another push button to de-energize the solenoid 593, thereby reversing the position of the valve 594 and causing the cylinder 483 to raise the pinch roll. Operation of this push button also de-energizes the solenoid 582 so the valve 583 reverses the flow of pressure fluid to the cylinder 428 to reverse the direction of movement of the feeder carriage. This push button also energizes the solenoid 585 to open the valve 586 thereby permitting movement of the feeder carriage at maximum speed. This push button further energizes solenoid 575 shifting the valve 576 to supply pressure fluid to the cylinders 526 and 538 for raising the jack rolls 515 and 516 so they will lift the tube 450 off of the supporting rollers 441 and 442, and also closes the circuit for the motor 541 to drive the jack roll 515 in a reverse direction.

As the feeder carriage withdraws the tube a cam 601, supported on the under side of the framework for the feeder carriage, actuates a

switch 602, supported on the main carriage, to de-energize the solenoid 585, closing the valve 586 so the speed of the feeder carriage is reduced to a rate determined by the setting of the throttle valve 592. The jack roll 515 moves the tube 450 axially to a point where its end clears spring-pressed actuating arm 604 for a switch 605, which is carried by a bracket 606 on one of the jack members 519. Actuation of the switch 605 in this manner energizes solenoid 607 which operates valve 608 to connect conduit 609 from the piston (inner) end of cylinders 547 and 555 to the pressure fluid conduit 568 for moving the pistons in these cylinders outwardly, thereby raising the "kick-out" arms 542 and 543 to discharge the tube 450 from the machine onto the skids 544. As the tube is discharged onto the skids 544, it actuates a switch 611 which de-energizes the solenoid 607 and reverses the valve 608 to connect line 612 from the cylinders 547 and 555 to the pressure fluid conduit 568 for lowering the "kick-out" arms. Actuation of this switch also stops the motor 541 and de-energizes solenoid 575 to lower the jack rolls 515 and 516. The solenoid 566 is also de-energized so the cylinders 509 and 512 raise the receiving arms 491 and 492 to their upper position for receiving another tube. The same switch 611 also de-energizes the solenoids 585 and 598 to return the valves 586 and 599 to their normally closed positions. In this manner, the various elements of the feeding apparatus are returned to their original position to begin another cycle of operation.

Summary

Both embodiments portray the invention in feeding apparatus particularly adaptable to continuous types of conveyer systems where metal tubes are carried through a series of operations without materially interrupting their flow. Automatic or semi-automatic operations move one tube at a time transversely into the feeding machine where it rests on a pair of supporting rollers in alignment with the swaging hammer and is axially engaged by a pusher element. In this position, the tube is revolved about its own axis as it is fed into the swaging hammer. After the hammer has pointed the end of the tube, the tube is withdrawn and discharged transversely from the machine in the direction opposite to that from which it was received.

The rotating supporting rollers are adjustably positionable with respect to the swaging hammer to accommodate tubes of different lengths. These rollers are also adjustable vertically according to diameter of the tubes being handled.

As illustrations of arrangements for providing driving friction to revolve the tube as it is fed into the hammer, the drawings show one machine having rubber-tired supporting rollers and the other provided with a pinch roll movable vertically to engage the tube opposite to the rotating supporting rollers. To avoid slippage when the hammer engages the tube, the supporting rollers may be driven through a resilient coupling permitting them to stop rotating

momentarily during each hammer blow without disturbing the driving power.

The constructions described above and illustrated in the accompanying drawings are preferred embodiments of the invention. As many changes could be made in these constructions without departing from the invention, as defined by the appended claims, it is intended that the description and drawings shall be interpreted as illustrative and not in a limiting sense.

What I claim is:

1. In apparatus of the character described, a carriage for supporting, feeding and turning an elongate cylindrical article, comprising a frame movable along a track, a pair of supporting rollers mounted on said frame for rotation about axes extending substantially parallel to said track and spaced transversely of said frame to support said article with its axis substantially parallel to said track, receiving arms pivoted on said frame and normally positioned to receive and hold said article above said rollers, and means responsive to the movement of an article onto said receiving arms for lowering said arms to rest the article on said rollers.

2. In apparatus of the character described, a carriage for supporting, feeding and turning an elongate cylindrical article, comprising a frame movable along a track, a pair of supporting rollers mounted on said frame for rotation about axes extending substantially parallel to said track and spaced transversely of said frame to support said article with its axis substantially parallel to said track, receiving arms pivoted on said frame and normally positioned to receive and hold said article above said rollers, means responsive to the movement of an article onto said receiving arms for lowering said arms to rest the article on said rollers, discharging arms pivoted on said frame and normally positioned below an article supported on said rollers, said discharging arms being movable to remove the article from said rollers, and means responsive to movement of the discharged article over said discharging arms for returning said arms to their normal position.

FRANK S. LAMPARD.
